UNITED STATES PATENT OFFICE.

JOHN EDWARD CONDON, OF NEW YORK, N. Y., ASSIGNOR OF ONE-HALF TO GEORGE F. MAGUIRE, OF NEW YORK, N. Y.

TALLY OR CHECKING SYSTEM.

994,819.

Specification of Letters Patent. Patented June 13, 1911.

Application filed July 23, 1904, Serial No. 217,882. Renewed November 11, 1910. Serial No. 591,871.

To all whom it may concern:

Be it known that I, JOHN EDWARD CONDON, a citizen of the United States, residing at New York, borough of Manhattan, 5 county of New York, and State of New York, have invented certain new and useful Improvements in Tally or Checking Systems, of which the following is a specification.

10 My invention consists in a checking or tally system adapted particularly for use in restaurants and hotels for the purpose of enabling cashiers or checkers to keep an accurate check or tally on orders given by the 15 patrons thereof.

It contemplates a system wherein the prices of the various articles ordered can be simultaneously stamped on the cashier's sheet and waiter's check and wherein for 20 this purpose the waiter's check can be expeditiously and accurately placed in register with his individual account on the cashier's sheet.

It further provides a system which insures absolute harmony between the waiter's 25 check and the cashier's sheet, thereby eliminating to a great extent any fraudulent practices on the part of dishonest waiters. In the event of the loss of a waiter's check 30 after the same has been recorded or tallied, it presents an easy way of determining the amount of said check.

With these objects and others of a similar 35 nature in view, I provide a tally sheet separated or divided into columns, corresponding to the individual accounts of the waiters, which columns are separated from each other by shoulders, ridges, elevations or other means whereby the waiter's check is 40 adapted to be quickly placed in register with his column on the tally sheet and the prices of the articles on his check simultaneously stamped by means of a double stamp or die on the check and sheet.

45 The invention will be readily understood from the following detailed description thereof taken in conjunction with the accompanying drawings wherein—

Figure 1 is a plan view of the cashier's 50 sheet; Fig. 2 is a plan view of the waiter's check; Fig. 3 shows the cashier's sheet with the waiter's check placed thereon in position for the stamping operation; Fig. 4 is an edge view of the tally sheet; and Fig. 5

is a perspective view of the double stamp 55 or die.

In the drawings, I have designated the cashier's tally sheet by A, the waiter's slip by B, and the die by C. In the form of tally sheet illustrated, the said sheet or tablet is 60 made up of overlapping sections, *a*, the edges, *b*, of which serve as the lateral edges or boundaries of the columns, *c*. These columns have headings, *d*, and, excepting the first and last, are numbered 1, 2, 3, 4, etc., 65 to correspond to the numbers by which the waiter's are designated. The sheet contains one or more spaces, *e*, above the said headings, on which may be designated, if desired, the name of the hotel or restaurant, 70 the date of the checking, etc. It also contains two or more horizontal divisions, *f*, *g*, near the bottom to enable the cashier to insert the "totals" of each waiter, and adjoining spaces for the auditor to check off 75 the cashier. The end column may be used also for getting the totals along the different horizontal lines of figures, thereby providing a check on the complete totals obtained by adding the individual columns of the 80 waiter's.

It will be noted that in the construction of the tally sheet, as heretofore described, there is a shoulder, *b*, extending upwardly from the tabulating surface of each column, 85 *C*, each shoulder intervening two adjacent tabulating columns. The waiter's check, *B*, numbered serially 1^a, is of the usual form, containing thereon the number of the waiter, and providing spaces for enumerating the different articles ordered and their prices. The stamp or die, *C*, of which there would be a series running from five cents up, is of the usual shape, and it contains duplicate numbers which are spaced a proper distance apart. 90 95

To illustrate the method of using my system, I will give a concrete example. Suppose a patron orders grape fruit, the price of which we will say is 35 cents. The 100 waiter takes the order, writing the name "grape fruit" on his check; he then goes to the cashier or checker who takes the check, places it on his tally sheet against the edge, *b*, in column No. 6, the column assigned to the particular waiter; he then takes his stamp or die with the number 35 in duplicate on the bottom thereof, and si- 105

multaneously, by a single operation, stamps 35 on the waiter's check and also on the tally sheet. The waiter then takes the check and proceeds to fill the order. Like orders are 5 filled in this way, and it is obvious that if desired the complete order may be checked at one time. It will be noted that the sales in the column of a particular waiter must agree with those on his separate slips, hence 10 there is no reasonable cause for error or confusion. Further, on account of the raised partitions or shoulders, *b*, the waiter's check can be quickly and accurately adjusted or brought into register with his individual column; hence the work of checking is materially expedited over the present methods in use wherein the columns are separated by lines merely and the stamping usually done by a single stamp or die, there- 15 by requiring a separate operation in stamping each item on the check and on the tally sheet.

My device is simple, economical and easily operated, and in practical use has proven of 20 great utility.

It will be obvious that changes and modifications may be made in the structure as described, which illustrates merely one form of my invention, and I therefore reserve the 25 right to make any and all changes, such as the use of equivalents, which come within the spirit of my invention as set forth herein. It will be apparent, for instance, that instead of making the tally sheet from separate sections, it might be made by properly rolling or pressing a single sheet so as to produce the desired elevations or demarcations therein.

Having thus full described my invention, 30 what I claim as new and desire to secure by Letters Patent is:—

1. In a system of the class described, a tally sheet having tabulating columns, and shoulders between said columns, each shoulder 35 extending upwardly from the surface of a column adjacent thereto, said shoulder being adapted to form an abutment for a waiter's check, the adjacent tabulating columns being exposed on either side of a shoulder intervening the surfaces of said columns.

2. In a system of the class described, a tally sheet having parallel tabulating columns, and a plurality of shoulders, each of said shoulders lying between two adjacent 50 columns, each shoulder extending upwardly from the surface of one of said columns, said shoulders forming an abutment against which is adapted to be placed the edge of a waiter's check whereby the surface of the

check is adapted to lie substantially flush 60 with the surface of one tabulating column and the desired data may be stamped simultaneously on the check and in the column.

3. In a system of the class described, a tally sheet having certain columns bounded 65 by shoulders intervening said columns, and parallel demarcations above and below said columns and at right angles thereto.

4. In a system of the class described, a tally sheet composed of columns formed by 70 overlapping a series of independent sections, whereby the edges of the sections serve as the lateral boundaries of the columns.

5. In a system of the class described, a tally sheet having parallel tabulating 75 columns bounded by shoulders forming parts of the sheet, and a check, the side of which is adapted to be placed in abutting engagement with the edge of one of said shoulders, whereby the check is adapted to lie in substantially flush relation to one of said columns, and the check and column may be simultaneously stamped.

6. In a system of the class described, a tally sheet having a horizontal space within parallel boundary lines and containing the designations of the waiters, a plurality of parallel vertical columns bounded by intervening shoulders, and another horizontal space within parallel boundary lines, said 90 last mentioned space intersecting with said vertical columns.

7. In a system of the class described, a tally sheet having two horizontal spaces, each being within parallel boundary lines, 95 one of which has designations for the waiters, vertical columns intermediate said horizontal spaces, and a plurality of shoulders, one shoulder being at one side of each vertical column, each shoulder extending 100 upward from the surface of one of said columns.

8. In a system of the class described, a tally sheet formed with parallel tabulating columns, one wall or boundary of each column extending upwardly from the adjacent edge of the column preceding it, whereby a check may be placed against the wall or boundary of one column and be assembled in substantially flush relation to the surface of 110 the adjacent tabulating column.

In testimony that I claim the foregoing as my invention, I hereunto sign my name in the presence of two subscribing witnesses.

JOHN EDWARD CONDON.
